UNITED STATES PATENT OFFICE.

FREDERICK H. HAMILTON, OF NEWARK, NEW JERSEY, ASSIGNOR OF ONE-HALF TO ROBERT JAEGER, OF LINDEN, NEW JERSEY, AND ONE-HALF TO CHARLES A. RYBERG, OF BROOKLYN, NEW YORK.

DOOR CHECK AND CLOSER.

Application filed November 19, 1926. Serial No. 149,392.

This invention relates to closing devices as applied to common swinging doors hinged to their frames in a vertical plane and has as one of its objects the provision of a noiseless, automatic means to close a door in a quiet manner.

It is a further feature to provide an operating means of unusually simple character, easy to attach and of moderate expense to manufacture.

Door closing devices of the usual types are objectionable in appearance, costly to construct and, due to the pneumatic or hydraulic elements employed, require adjustment and eventually wear to such an extent as to become useless.

It is therefore the principal purpose of the present invention to provide a device in which the disadvantages of ordinary checks and closers are avoided.

These features of the invention are attained by the novel construction and combination of parts hereinafter described and illustrated in the accompanying drawing, forming an important component of this disclosure, and in which:—

Figure 1 is a top plan view of the device showing the door in a closed position.

Figure 2 is a similar view of the same showing the door partially opened.

Figure 3 is a side elevational view thereof, drawn to an enlarged scale.

Figure 4 is a fragmentary partial transverse sectional view illustrating the arm pivots.

Referring in detail to the drawing, the numeral 10 generally designates a door frame to which is attached by hinges 11 to one of the longer edges of a door 12.

Secured to the lintel of the door frame, at a point near the upper end of the door 12 opposite the hinged edge, is a right angle bracket 13 carrying a stud 14 provided with a body 15 around which is coiled a torsion spring 16, its upper end 17 being set in the bracket 13 and the lower end 18 being set in the end of a thin flat arm 19 rotatably mounted on the stud 15 the action of the spring being to press the arm in the direction of the wall containing the door opening.

The opposite end of the arm 19 is pivoted on a stud 20, surrounded by a spacer 21 be-

tween a washer 22 and the head 23 of the stud the opposite end of which is engaged by a nut 24 resting on the washer.

Mounted on the spacer 21 is a helical torsional spring 25, one end 26 of which engages the arm 19, and the other end 28 engages a second arm 27, the last named arm being rotatable on the stud 20 intermediate the spacer 21 and the head of the stud, the spring operating to press the door into a closed position.

The outer end of the arm 27 is rotatably secured on the reduced portion of an internally threaded stud 29, intermediate its shoulder 30 and a washer 31 and is held in position by a screw 32, the stud being riveted at 33 to a right angled bracket 34 fixed on the door 12 in register with the bracket 13.

Coiled about the stud 29 is a torsion spring 35, one end 36 of which is set in the arm 27 and the other end 37 in the bracket 34, this spring also exerting its tension in an effort to close the door, as do the other springs 16 and 25.

Pivoted to the arm 27 at 38 is a bar 39 having a curved portion 40 the axis of the curve being taken from the pivot, in close relation to a stop 41 fixed on the arm engageable with a projection 29 formed on the end of the bar.

The bar 39 carries at its outer end a pivot 42 on which is mounted a wheel 43 engageable with the arm 19.

Fixed intermediate the washer 22 and the nut 24 is one end of a tension spring 44, the other end being secured on a post 45 attached on the bar 39, the tension of the spring being exerted to press the wheel firmly against the bar, which action becomes intensified as the door assumes a nearly closed position.

Thus in operation, when the door is closed as in Figure 1, the spring 44 is expanded. Upon opening the door, the arms 19 and 27 spread on the pivot 23 against the action of the torsion spring 25. At the same time the spring 44 contracts causing the wheel 43 to ride on the arm 19 under constantly lessening pressure.

Upon closing the door, the spring 44 expands and when the wheel 43 engages the arm 19 to ride thereon the speed of the door is checked.

It is to be noted that the main elements are made from flat stock and that the cost of construction is thereby rendered very low.

Although the foregoing is descriptive of the preferred embodiment of the invention, it will be apparent that minor changes may be made in its construction, without the exercise of invention or conflicting with the scope of the claim hereto appended.

Having thus described my invention, what I claim as new and desire to secure by Letters Patent, is:—

A door closing device comprising a pair of pivoted arms attached respectively to a

door and the lintel thereof, a spring adapted to swing said arms inwardly on their pivot, a bar pivoted to the arm attached to the door, a grooved wheel rotatable on the free end of said bar to engage the other arm, a tension spring extending from the arm pivot to said bar, and a stop carried in the arm adjacent the bar pivot, said stop limiting the swing of said bar in both directions.

Signed at New York in the county of New York and State of New York this 14th day of October, A. D. 1926.

FREDERICK H. HAMILTON.
